UNITED STATES PATENT OFFICE.

ARCHIE F. LOVE AND JOHN NICOLETTI, OF ROCHESTER, NEW YORK, ASSIGNEES TO
EASTMAN KODAK COMPANY, OF ROCHESTER, NEW YORK, A CORPORATION OF
NEW YORK.

PRESS-GUARD.

1,343,178.

Specification of Letters Patent.

Patented June 8, 1920.

Application filed May 27, 1919. Serial No. 300,169.

To all whom it may concern:

Be it known that we, ARCHIE F. LOVE and JOHN NICOLETTI, citizens of the United States of America, residing at Rochester, in the county of Monroe and State of New York, have invented certain new and useful Improvements in Press-Guards, of which the following is a full, clear, and exact specification.

10 Our present invention relates to punch presses and similar intermittently operated machines in which there is danger of injury to the hands of the workman, due to the placing and removal of work under the 15 operating parts of the machine. It has for its object to provide an automatic guard for ejecting the hand of the operator from the danger zone before the machine functions, and a further object is to provide a guard 20 which will prevent the operator from reaching around behind the ejecting guard or guards thereby taking a chance of injuring his hand. To these and other ends the invention resides in certain improvements and 25 combinations of parts all as will be hereinafter more fully described, the novel features being pointed out in the claims at the end of the specification.

In the drawings in which like reference 30 characters indicate the like parts throughout:

Figure 1 is a front elevation of a portion of a press provided with a guard embodying our invention;

35 Fig. 2 is a side elevation of the entire press;

Fig. 3 is a detail front elevation of the side guard with a portion broken away;

Fig. 4 is a side elevation similar to Fig. 3;

40 Fig. 5 is a detail section on line 5—5 showing the bearing for the swinging side guard.

In the drawing we have shown a press equipped with a double wing guard, such 45 as is shown in Patent No. 1,178,168 to MacDonald and Dougherty, April 4, 1916, although our improvement applies equally well to other forms of guards wherein the hand of the operator is ejected to one side 50 before the press operates. The press shown in the drawings comprises a frame 1, mounted on a base or table 2, at the bottom of which a foot lever 3 is fulcrumed at 4. Power is applied to a fly wheel 5 by a belt 55 not shown, there being a clutch 7 between the

fly wheel 5 and shaft 6, upon which it freely turns. This clutch 7 is operated at the will of the workman by depressing foot lever 3 which actuates clutch 7 through a connecting rod 10. In the press illustrated the ram 60 8 is attached to the shaft 6 by a crank 9, so that each revolution of the wheel 5 will reciprocate the ram once. In this type of machine each depression of foot lever 3 causes the clutch 7 to key the wheel 5 to the 65 shaft 6 for one revolution. The work 11 is placed on a bed 12, so that the ram 8 carrying the necessary tool performs its operation in a single stroke. In order to protect the operator's hands from injury 70 by the ram 8 when he fails to move quickly enough to avoid the stroke of the ram, or when the clutch slips or breaks, or the foot lever is accidentally displaced, guards have been designed to eject the operator's hand 75 from the danger zone before the machine functions.

We will briefly describe the guards illustrated in the drawings, with which our improved guard coöperates. Brackets 29 are 80 fastened to the frame 1 of the press by bolts 13, forming bearings for a yoke 14, which is connected to the brackets by pins 15, so that the yoke may be easily removed, or, by removing one of the pins 15 may be 85 swung about the other pin so that the parts hereinafter described are accessible. The yoke 15 has a bushing in which a shaft 16 is mounted. On and revolving freely about shaft 16 there is a member 17 which carries 90 an arm 18 to which is affixed a guard wing 19. This guard is preferably made of transparent celluloid so that the work can be seen when the guard is in front of it, but other material such as wire mesh may be 95 used. In order to operate this guard before the machine functions it is connected to the foot lever 3 in the following manner: A link 20 connects member 17 to one arm of a bell crank lever 21, which is in turn connected by links 22 and 23 to a long lever 24 pivoted to frame 1 by a pin 25. A rod 26 connects this lever with the foot lever 3. The rod 26 is preferably made adjustable along lever 24 by an adjustable slide 100 27 having a set screw 28. To operate this guard the foot lever 3 is depressed. This lowers lever 24 through rod 26, causing the long arm 21' of bell crank lever 21 to move down through the pull exerted by links 110

22 and 23. This thrusts link 20 to the left, thereby swinging member 17 about shaft 16 causing the guard wing 19 to move from the position shown in full lines to the position shown in dotted lines, Fig. 1. Rod 10 is adjusted so that clutch 7 will not operate until the guard has completed over a half of its stroke, thereby insuring the ejecting of the operator's hand in case the ram is accidentally functioned.

5 Directly behind the guard wing 19 there is a second wing 30 of similar shape and size. This is operated through the same path as guard 30, but is actuated by the ram 10 instead of by foot treadle 3. The reason for this second guard is that if the clutch should break the ram might operate without having the foot lever 3 depressed. With this second guard the ram 8 would operate 15 the guard 30 as hereinafter described preventing an accident to the operator's hand. Guard 30 is mounted on an arm 31 attached to a segment 32 revoluble about shaft 16. This segment 32 has a cam slot in which a 20 roller (not shown) carried by ram 8 moves, so that the guard 30 is moved across the front of the bed 12 thereby knocking the operator's hand to one side when the first guard fails to work.

30 It has been found in practice that the above described mechanism is insufficient to prevent injury, since a workman will sometimes reach around the guards from the side to adjust the work after the guard has 35 moved to the position shown in dotted lines Fig. 1 and before the ram has descended, thereby frequently being injured. To prevent this, and to further add to the safety of the operator we provide an additional 40 swinging guard 40, attached to an arm 41 which is mounted on a stub shaft 42 fastened into the yoke 15 see detail Fig. 5. The guard or wing 40 is preferably made of transparent material such as celluloid. On 45 the arm bearing 43 there is a lug 44 adapted to engage a stop 45 on the yoke 15, so that the guard cannot be rotated toward the work farther than shown in full lines Fig. 1 while at the same time allowing it to 50 swing outwardly, see dotted lines Fig. 1. It will readily appear that an operator, seeing that his work needs adjusting after the guard is operated and before the ram had descended, cannot quickly reach around the 55 guard and take a chance of fixing the work before the ram functions. Moreover, if his hand is thrust to one side by either guard, the swinging guard revolves on its pivot to allow the hand to be thrown off the table 60 and not injured as would be the case if the side guard were stationary. We preferably make the side guard arm 41 with a curved portion 46 to avoid striking the long lever 24. In order to make this guard easily removable for cleaning the machine, changing

65 dies and the like, we provide a spring lock consisting of a heavy spring wire 47 mounted on one side of the arm 41, movable in a slot 48 so that it will latch into a slot 49 in a stub shaft 42, which is mounted on 70 yoke 14, see Fig. 5. A pin 50 holds the latch in locked position, preventing the accidental slipping off of arm 41. To remove the side guard 40, withdraw pin 50 and draw back spring 47 into position shown in 75 dotted lines Fig. 3 thereby disengaging the spring from the slot 49 and slide guard arm 41 off the stub shaft 42. Reverse the operation to replace.

80 From the foregoing description it will be seen that we provide a simple guard which will prevent many of the accidents now resulting from careless operators. It is simple to construct, durable and efficient in use. We do not wish to limit the use of 85 our side arm guard to a double wing press guard such as is herein described for it will be obvious that it is equally well adapted for use with a single wing guard or any guard which operates in front of the 90 press and ejects the operator's hand to one side of the machine.

Having thus described our invention what we claim as new and desire to secure by Letters Patent of the United States is: 95

1. In a machine having an intermittently operating mechanism mounted on a frame, the combination of a safety guard pivoted to the frame adapted to swing across a portion of the frame, to prevent access to the 100 intermittently operating mechanism during the time that it is operating, with a second guard pivoted to the frame adapted to be swung relative to the frame allowing egress but not ingress, protecting another portion 105 of the frame from that covered by the first mentioned guard.

2. In combination with a machine having exposed intermittently operating mechanism mounted on a frame, a movable guard carried by the frame connected with the intermittently operated mechanism so as to operate in timed relation thereto, crossing the front of said intermittently operating parts and returning at each cycle of movement, 115 and a second guard normally stationary, adapted to prevent access to the mechanism from a side of the machine, said second guard co-operating with said first guard when an operator's hand is ejected from 120 beneath the operating parts of the first guard.

3. In combination with a machine having an exposed intermittently operating mechanism, a movable guard adapted to be 125 swung in front of said mechanism in timed relation to its operation and a second normally stationary guard mounted at one side of said movable guard and preventing access to said mechanism from that side, said 130

normally stationary guard being movable away from said movable guard, so that an object struck and moved by the movable guard will be permitted egress past said 5 normally stationary guard.

4. In a safety device for punch presses the combination of a punch press consisting of a frame, bed, a ram movable in the frame, with safety guards, one adapted to move in 10 timed relation to the ram and the other normally stationary, the second mentioned guard adapted to swing away from the bed, only when under the impulse of a force directed away from the movable guard.

15 5. In a safety device for punch presses the combination of a punch press consisting of a frame, a bed, a ram, operating mechanism for moving the ram in the frame, with guards to protect the limbs of an operator, 20 the guards comprising wings one of which is connected to operate in timed relation to the ram protecting a portion of the bed across which work is placed upon the bed, the other wing independent of the operating 25 mechanism and adapted to protect another portion of the bed.

6. In a safety device for punch presses the combination of a punch press consisting of a frame, a bed, a ram movable in the frame, 30 and mechanism for moving the ram, with safety guards, two guards attached to the mechanism which moves the ram so as to function in timed relation thereto, the said guards protecting a portion of the bed, and 35 a third guard independent of the ram operating mechanism to protect a portion of the bed not protected by the first two guards.

7. In combination, a machine having an exposed operating mechanism, a guard piv- 40 oted on the machine to swing from one side across the front thereof and a second normally stationary guard mounted on the side of the machine and pivoted to swing in the direction that the first mentioned guard 45 moves as it swings into operative position.

8. In a safety device for machines having intermittently operated parts mounted on a frame, the combination of a safety guard operated through the intermittently operat- 50 ing parts to protect a front portion of the frame during the time in which the machine functions, with a supplementary safety guard hingedly connected to the frame to prevent access to the moving mechanism 55 from the side, there being a stop on the guard limiting its movement in one direc- tion.

9. In a safety device for punch presses, the combination of a punch press compris- 60 ing a frame, a lug on the frame, a bed, a ram movable over the bed, with safety guards, one swinging intermittently under the impulse of the ram moving mechanism and the other movable in one direction un- 65 der the impulse of a force exerted by the first mentioned guard, there being a stop on the second guard coöperating with a lug on the frame to prevent the movement of the second guard toward the first guard from 70 its normal stationary position.

Signed at Rochester, New York, this 26th day of May, 1919.
